US00D916185S

(12) **United States Design Patent** (10) **Patent No.:** **US D916,185 S**
Spiring (45) **Date of Patent:** **** Apr. 13, 2021**

(54) **MODEL OF AN ATOM**

- (71) Applicant: **Spiring Enterprises Limited**, Billingshurst (GB)
- (72) Inventor: **Philip Spiring**, Billingshurst (GB)
- (73) Assignee: **Spiring Enterprises Limited**, Billingshurst (GB)
- (**) Term: **15 Years**
- (21) Appl. No.: **29/677,587**
- (22) Filed: **Jan. 22, 2019**

(30) **Foreign Application Priority Data**

- Oct. 23, 2018 (EM) 005805306-0001

(57) **CLAIM**

The ornamental design for a model of an atom, as shown and described.

DESCRIPTION

FIG. 1 is a perspective view of a model of an atom showing my new design;

FIG. 2 is a front side view thereof;

FIG. 3 is a rear side view thereof;

FIG. 4 is a left side view thereof;

FIG. 5 is a right side view thereof;

FIG. 6 is a top view thereof; and,

FIG. 7 is a bottom view thereof.

1 Claim, 7 Drawing Sheets(56)
